UNITED STATES PATENT OFFICE.

WILLIAM H. WOLFE, OF FISHERSVILLE, VIRGINIA.

EGG-CARRIER.

SPECIFICATION forming part of Letters Patent No. 227,870, dated May 18, 1880.

Application filed March 31, 1880. (No model.)

To all whom it may concern:

Be it known that I, WILLIAM H. WOLFE, a citizen of the United States, residing at Fishersville, in the county of Augusta and State of Virginia, have invented certain new and useful Improvements in Egg-Carriers; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 This invention relates to an improved device for packing and transporting eggs; and it has for its object to provide a system of drawers confined in a suitable packing-case and provided with supports for the eggs, by which the 20 same may be held separately and out of contact with each other and in a vertical position, whereby all danger of breakage in handling and transportation is avoided, as more fully hereinafter specified.

25 These objects I attain by the mechanism illustrated in the accompanying drawings, in which—

Figure 1 indicates a perspective view of my apparatus with the door partially raised, as 30 shown in dotted lines; and Fig. 2, a vertical sectional view of my apparatus, showing the egg-supporting devices.

The letter A indicates the exterior or packing-case of my improved device, which is rectangular in shape and provided with an opening in front, which is adapted to be closed by means of a door, C, sliding in grooves D at each side of the casing. The casing is provided with a loosely-attached hasp, E, adapted 35 to fit over a staple, F, on the sliding door, by

means of which the door may be securely fastened by an ordinary padlock. The interior of the casing is provided with ways or guides G, upon which are supported the sliding drawers H. The said drawers may be of any desired 45 number, and each is provided with two horizontal partitions, I K, provided with circular openings L M, in which the eggs are placed and by which they are supported. The openings in the lower partition are directly below 50 those in the upper partition, the openings in the upper partition being larger than those below, and of such size to embrace the eggs around their larger parts, the lower apertures being of a size to receive and hold the ends of 55 the eggs.

The operation of my invention will be readily understood, in connection with the above description, without further explanation.

The outer frame or casing is provided with 60 casters or rollers N, by which the device may be readily moved from place to place.

Having thus fully described my invention, what I claim, and desire to secure by Letters Patent, is—

65 In a device for packing and transporting eggs, the combination of the outer casing, A, provided with a door, C, and devices for locking the same, with the sliding drawers adapted to fit in said casing, and provided with partitions I K, having apertures L M, the upper apertures being larger than those below, so as 70 to hold the eggs in an upright position, substantially as set forth and shown.

75 In testimony whereof I affix my signature in presence of two witnesses.

WILLIAM H. WOLFE.
